FAN INLET GUARD AND A METHOD OF
MANUFACTURING THE SAME

Matthew C. Allin, Weston, Ontario, Canada, assignor to Riley Engineering & Supply Co. Ltd., Toronto, Ontario, Canada, a corporation of Canada

Application February 21, 1933, Serial No. 657,824

8 Claims. (Cl. 22—203)

This invention relates to a fan inlet guard and a method of manufacturing the same, the construction being adapted to admit air to the interior of a fan housing, to protect the operator from injury, and to prevent foreign bodies from entering the fan and damaging the rotating fan wheel.

It has been the practice heretofore to mount screens over the air inlets of fans, but the prior constructions have been expensive to manufacture, and it has been difficult to provide the desirable stream-lined air passage without complicating the construction and adding considerably to its cost. Furthermore, prior arrangements were lacking in strength and were frequently distorted or broken and rendered unsightly by accidental blows.

It is accordingly one object of the invention to provide a fan inlet guard which is simple and inexpensive to manufacture and which is very strong in proportion to its weight.

It is a further object of the invention to provide a fan inlet guard which is attractive in appearance, and which will lead the air smoothly 25 and gradually into the center of the fan wheel without producing undesirable eddy currents in the air stream.

It is a further object of the invention to provide a method of manufacturing fan inlet guards, which is simple and inexpensive to carry out in practice.

It is a further object of the invention to provide a method of manufacturing fan inlet guards which will produce a substantially integral and very strong construction.

With these and other objects in view, as will be apparent to those skilled in the art, the invention resides in the combination of parts and the steps of the process set forth in the specification and covered by the claims appended hereto.

In accordance with my invention I provide a fan inlet guard comprising a perforated screen, preferably of wire-mesh, having its peripheral portion embedded in a cast metal frame. In the preferred construction, the frame is circular, and the screen is dished outwardly. The frame may be shaped to provide an inwardly-tapering stream-lined air passage. The construction is manufactured by first providing a screen and then casting the metal frame into engagement with the peripheral portion of the screen. The screen is preferably dished before the casting operation, and it may be embedded in a core with the peripheral portion of the screen projecting

outwardly beyond the core, molten metal being poured around the core to form the frame.

Referring to the drawing illustrating one embodiment of the invention, and in which like reference numerals indicate like parts,

Fig. 1 is a side elevation of a fan showing my improved inlet guard applied thereto;

Fig. 2 is a section on the line 2—2 of Fig. 1;

Fig. 3 is a partial sectional view of a core box; and

Fig. 4 is a section through a mold ready for the pouring operation.

The embodiment illustrated comprises a fan housing 10 provided with the usual scroll-shaped peripheral wall, and having a rotatable fan wheel 12 of well-known construction mounted therein. An inlet opening 14 (Fig. 2), preferably circular in shape, is provided in the side wall of the housing 10 to admit air to the fan wheel 12.

In order to prevent foreign bodies from reaching the fan wheel, and also guide the air into the interior of the wheel, I provide a perforated screen 16 having its peripheral portion embedded in a cast metal frame 17. The screen 16 is preferably circular in shape and formed of a rather coarse wire-mesh fabric. The frame 17 is shown provided with an annular flange 18 which is riveted or otherwise secured to the fan housing 10 surrounding the opening 14. The frame 17 projects inwardly through this opening, and tapers smoothly and gradually towards the fan wheel to form a stream-lined air passage. The screen 16 is dished outwardly, and hence has great strength to resist accidental blows.

In the manufacture of my improved fan inlet guard, I first provide the screen 16 and then cast the frame 17 into engagement with the peripheral portion thereof. The screen is preferably bent into a dished shape prior to the casting operation, by means of dies or in any other suitable way.

In Fig. 3 I have shown a partial section through a core box which may be conveniently utilized in carrying out my novel process. This core box comprises a lower part 20 and an upper part 21, these parts being shaped to provide the desired stream-lined form for the interior surface of the cast frame. An annular groove 22 is provided between the parts 20 and 21, and in making the core the peripheral portion of the screen 16 is placed in this groove and the remainder of the screen is embedded in the core sand. Thus, when the core is completed, the peripheral portion of the screen will project outwardly beyond the core. It will be noted that the maximum internal di-

ameter of the core box occurs intermediate the height of the upper part 21, so that it will be necessary to form this part in a plurality of sections and withdraw each section in a radial direction, as will be understood by those skilled in the art.

After the core is completed it is placed in a mold and the frame 17 is cast around the core. In Fig. 4 I have shown a section through a mold ready for the casting operation. This mold, which may be prepared in accordance with the usual and well-known foundry practice, comprises a cope 24 and a drag 25 supported on a bottom board 26. The core 28, with the screen 16 embedded therein, is located in the mold between the cope and the drag, and an annular mold cavity 29 surrounds the core. The peripheral portion of the screen projects into this cavity. The mold is provided with the usual gate 31, sprue 32, and pouring basin 33. Molten metal, such as iron, is poured into the mold to fill the cavity 29 and form the annular frame 17. As this metal solidifies it provides a firm and substantially integral joint with the screen 16. The frame 17 will shrink appreciably as it cools, and this shrinkage will simply cause the dishing of the screen to be slightly more pronounced. There will be no buckling or irregular distortion of the screen, as would be the case if the screen were originally flat.

It will now be apparent that I have provided a fan inlet guard which is simple and inexpensive to manufacture and effective for the purpose intended. The construction is attractive in appearance, and provides a smooth stream-lined passage to conduct air into the fan wheel. The integral bond between the cast frame and the screen, together with the arched or dished form of the screen, provides great strength without excessive weight. Consequently the screen will withstand comparatively heavy blows without injury or distortion. My improved process of manufacture is simple and requires no expensive equipment. It can be readily understood and carried out by workmen of ordinary skill in the foundry art.

Having thus described my invention, what I claim as new and desire to secure by Letters Patent is:

1. A fan inlet guard comprising a dished cir-

cular wire-mesh screen having its peripheral portion embedded in an annular cast metal frame.

2. A fan inlet guard comprising an outwardly dished circular wire-mesh screen having its peripheral portion embedded in an annular cast metal frame, the frame being shaped to provide an inwardly-tapering stream-lined air passage. 5

3. A fan inlet guard comprising a dished circular wire-mesh screen having its peripheral portion embedded in an annular cast metal frame, 10 the frame having an integral annular flange shaped to engage the wall of a fan housing.

4. The method of manufacturing a fan inlet guard comprising the steps of providing a substantially circular wire-mesh screen, bending the 15 screen into a dished shape, and casting an annular metal frame into engagement with the peripheral portion of the screen.

5. The method of manufacturing a fan inlet guard comprising the steps of providing a substantially circular wire-mesh screen, bending the 20 screen into a dished shape, embedding the dished screen in a core with the peripheral portion of the screen projecting outwardly beyond the core, placing the core in a mold having an annular 25 cavity surrounding the core, and pouring molten metal into the cavity to form an annular frame firmly united with the screen.

6. A fan inlet guard comprising an annular frame and a wire-mesh screen extending across 30 the opening in the frame, the ends of the wires forming the screen being embedded in the material of the frame, and the screen being dished to relieve stresses caused by temperature changes and to increase the strength of the screen. 35

7. A fan inlet guard comprising an annular frame shaped to provide an inwardly-tapering stream-lined air passage, and a wire-mesh screen extending across the passage, the ends of the 40 wires forming the screen being embedded in the material of the frame, and the screen being dished outwardly to relieve stresses caused by temperature changes and to resist external blows. 45

8. A fan inlet guard comprising an annular frame having an integral annular flange shaped 45 to engage the wall of a fan housing, and a dished wire-mesh screen extending across the opening in the frame, the ends of the wires forming the screen being embedded in the material of the frame. 50
